ROTARY SWITCH

George H. Erb, South Orange, N. J., assignor to
 Federal Telephone and Radio Corporation,
 Newark, N. J., a corporation of Delaware

Application May 7, 1943, Serial No. 485,969

1 Claim. (Cl. 200—6)

1

The present invention relates to electrical switches and more particularly to a multi-position switch having an indexing mechanism incorporated therewith.

Although indexing devices for switches are well known in the art, it is one purpose of the present invention to provide an improved assembly in which the switch contacts and the indexing mechanism are enclosed as a unit within a housing of relatively small size.

It is a further object of the invention to provide an indexing mechanism that will have a positive action but at the same time can be actuated with a minimum of effort.

It is another object of the invention to provide an indexing mechanism that will maintain the switch contacts in the position selected regardless of vibration or shocks that may be applied to the switch housing or to the control structure.

The invention still further contemplates an indexing device that includes interchangeable parts, so that by a proper selection of such parts the indexing mechanism can be made to respond to operating forces of any desired magnitude.

Other objects and advantages will be apparent from the following description of a preferred form of the invention and from the drawings, in which:

Fig. 1 is a sectional view of a switch assembly in accordance with the present invention;

Fig. 2 is a view along 2—2 of Fig. 1;

Fig. 3 is a view along 3—3 of Fig. 1, showing the inner rotor assembly;

Fig. 4 is a view along 4—4 of Fig. 1, showing the outer contact assembly;

Fig. 5 is a sectional view of the tube cradle of Fig. 1.

In Fig. 1 is shown a rotatable shaft 6 on which is mounted an insulating member 20 supporting a plurality of inner switch contacts 30. A plurality of rivets 32 respectively position inner contacts 30 on insulating member 20, this construction being also shown in Fig. 3. Each of these inner contacts 30 comprises a pair of flexible spring elements disposed in substantially parallel relationship and having ears on the outer corners thereof to facilitate engagement with stationary outer contacts 16, as will hereinafter be described.

A ring-shaped insulating member 12 (see also Fig. 4) supports and positions a plurality of outer stationary contacts 16, this ring-shaped insulating member 12 forming a part of the assembly housing, as can be seen from Fig. 1. The outer contacts 16 are spaced apart by a raised circular

2

portion 13 of member 12, and a plurality of rivets 18 respectively connect these outer contacts 16 with exterior terminals 14. Another raised circular portion 15 of insulating member 12 spaces and retains in position outer terminals 14.

On one side of insulating member 20 is a raised surface portion 21 shaped so as not to interfere with the positioning of contacts 30 by pins 32 (see Fig. 3). A slot in this portion 21 receives a pin 22 which extends through shaft 6, and is securely positioned thereby. Thus a rotation of shaft 6 will correspondingly rotate insulating member 20 as well as associated inner contacts 30.

15 A front cover 10 for the assembly fits against insulating member 12 and has a bushing 8 enclosing shaft 6. This bushing may be externally threaded to permit connection of the switch assembly to a suitable mounting. Between bushing 8 and the raised surface 21 of insulating member 20 are a washer 26 and a pair of spacers 24 and 26.

20 The extremity of shaft 6 is formed with a cup-shaped opening as shown in Fig. 1, and a tube 25 cradle 34 is insertably positioned in this opening. A tubular extending portion 35 of shaft 6 is formed axially thereof and passes through an opening 37 in tube cradle 34 (see Fig. 5). The extending portion 35 is peened over to securely 30 position on shaft 6 the cradle 34 and the insulating member 20.

25 A spring retaining tube 40 is securely attached to tube cradle 34 by means such as soldering, the tube cradle being shaped to receive the tube 35 40 as shown in Fig. 5. A spring 42 is compressibly positioned in tube 40, and a pair of spring guides 44 and 45 at the ends of spring 40 respectively contact an upper ball bearing 46 and a lower ball bearing 48. A rear cover 38 adjoins insulating member 12 and with this member and front cover 10 form a compact housing unit for the switch and indexing assembly.

30 Rear cover 38 is constructed as best shown in Fig. 2. A recess 47 on the inner surface thereof 45 is designed to receive the spring retaining tube 40. In the upper portion of recess 47 are formed three niches 49, 50 and 51 shaped to receive the ball bearing 46 which is partially enclosed within spring retaining tube 40. Ball bearing 48 rides 50 along the smooth lower surface of recess 47 as shown. Threaded openings 52 on cover 38, insulating member 12, and the front cover 10, receive screws (not shown) which when tightened tend 55 to form a relatively dust-proof enclosure for the assembly.

From Figs. 1 and 3 it can be seen that a rotation of the shaft 6 will rotate the insulating member 20 and the inner contacts 30. These contacts 30 will then selectively bridge or connect the outer contacts 16 (Fig. 4). The present disclosure is not limited to any combination or arrangement of circuits, but it will be obvious that a large number of switching variations within the scope of the invention can be obtained by altering the spacing of the outer contacts 16 and/or the design of the inner contacts 30.

As will be seen from Fig. 1, each spring contact 30 is designed as a pair of flexible sections disposed face to face so that an outer contact 16 may pass between these sections upon rotation of shaft 6, this construction insuring an electrical connection between the inner and outer contact elements. The ears on the corners of the inner contacts 30 are to guide the outer contacts 16 in passing between the sections of such inner contacts.

Assume now that the indexing mechanism is in the position shown in Figs. 1 and 2, that is, with the ball bearing 46 of spring retaining tube 40 in the central niche 50 in recess 47 of rear cover 38. Due to the tension of spring 42, spring guide 44 exerts pressure on bearing 46 to hold bearing 46 in niche 50, thus positioning tube 40 in place in recess 47. The resultant pressure of spring 42 in the opposite direction is exerted against spring guide 45 and ball bearing 48, but since bearing 48 rides along the smooth lower surface of recess 47 no opposition is offered by bearing 48 to a rotation of shaft 6.

When it is desired to actuate the shaft 6 to another of its contact positions, the angular movement of tube 40 will force ball bearing 46 against the sloping surface of niche 50, and sufficient pressure will result in a depressing of ball bearing 46 into tube 40 for a sufficient distance to permit the upper surface of bearing 46 to clear the sharp edge between niches 50 and 51 (or 49, depending on the direction of rotation of shaft 6). As soon as the bearing 46 enters niche 51 it will center the tube 40 in such niche due to the tension of spring 42. Thus a positive indexing operation results, and since the spring 42 permits the tube 40 to have a limited movement transversely of shaft 6 without the ball bearing 46 being displaced from the niches 49, 50 and 51, the disclosed structure will resist a shock or vibration applied to the shaft or housing in a direction perpendicular to the axis of the shaft and having a tendency to disturb the selected

relationship of the switch contacts 16, 30. Since it can also be seen from Fig. 1 that the spring retaining tube 40 does not directly contact the inner surface of rear cover 38, any vibration or other shock applied longitudinally along the axis of the shaft will be taken up by the spring contacts 30 and 16 without disturbing their circuit relationship, since the applied force is at right angles to their direction of rotation.

It should be noted that due to the relatively short radius of the indexing mechanism, little operating force need be applied to the shaft 6 to actuate the switch assembly. Furthermore it will be apparent that by removing the rear cover 38 the ball bearings 46, 48, the spring guides 44, 45, and the spring 42 may be quickly removed from the tube 40. By selecting a spring having a different degree of resiliency, the switch assembly can be made to respond to any desired operating force, this change being effected without disturbing in any way the switch contacts 30, 16, and without the necessity of breaking the circuit when the spring replacement is made.

While I have described above the principles of my invention in connection with specific apparatus, it is to be clearly understood that this description is made only by way of example and not as a limitation on the scope of my invention as set forth in the objects of my invention and the accompanying claim.

I claim:

In a compact rotary switch and indexing mechanism, a housing having a substantially dust-proof recess therein, said recess comprising two portions, one portion being substantially cylindrical and containing a plurality of radially projecting contacts, and the other portion being substantially the shape of two opposing sectors wherein the arcuate surface of one sector is smooth and the surface of the other sector contains a plurality of spaced-apart axial grooves, a rotatable shaft supported by said housing coaxial with said recess, one or more conducting elements carried by said shaft for bridging adjacent radially projecting contacts in said cylindrical portion of said recess, and an indexing mechanism within said other dual-sector-shaped recess portion comprising a transverse bearing holder mounted on the said shaft and a pair of bearings, one of said bearings directly engaging said axially grooved arcuate surface, and the other of said bearings directly engaging said smooth arcuate surface.

GEORGE H. ERB.
